UNITED STATES PATENT OFFICE

151,479

DESIGN FOR A LIGHT BOX FOR VIEWING
COLOR TRANSPARENCIES

William P. Way, Floral Park, N. Y.

Application March 23, 1946, Serial No. 127,853

Term of patent 14 years

(Cl. D61—1)

To all whom it may concern:

Be it known that I, William P. Way, a citizen of the United States, residing at Floral Park, in the county of Nassau and State of New York, have invented a new, original, and ornamental Design for a Light Box for Viewing Color Transparencies, of which the following is a specification, reference being had to the accompanying drawing, forming part thereof.

Fig. 1 is a perspective view of a light box for viewing color transparencies embodying my new design; and

Fig. 2 is an enlarged sectional view on substantially the plane of line 2—2 of Fig. 1.

The novel features of the design reside in a light box for viewing color transparencies having an inclined front wall with a viewing opening recessed about the edges for supporting color transparencies and having an inclined portion below the viewing opening carrying a light control

switch and below that a low, plain vertical front panel.

I claim:

The ornamental design for a light box for viewing color transparencies, substantially as shown and described.

WILLIAM P. WAY.
